Patented Dec. 29, 1914.

UNITED STATES PATENT OFFICE.

WILLIAM HUBELI WALDRON, OF HIGHLAND PARK, NEW JERSEY, ASSIGNOR TO JNO. WALDRON CO., OF NEW BRUNSWICK, NEW JERSEY.

BORDER-CUTTING MACHINE.

1,123,043.

Specification of Letters Patent. Patented Dec. 29, 1914.

Application filed May 9, 1914. Serial No. 837,389.

To all whom it may concern:

Be it known that I, WILLIAM HUBELI WALDRON, a citizen of the United States, and a resident of Highland Park, in the 5 county of Middlesex and State of New Jersey, have invented a new and Improved Border-Cutting Machine, of which the following is a full, clear, and exact description.

10 The invention relates to the manufacture of wall paper borders, and its object is to provide a new and improved border cutting machine arranged to enable the attendant to keep the border in accurate registration with the cutting roll.

In order to accomplish the desired result, use is made of an endless traveling band or apron driven from the cutting roll and in unison therewith, the said endless band having 20 one run arranged adjacent an edge of the border and the endless band having spaced registering means adapted to register with the spacing marks of the repeating design on the border.

25 A practical embodiment of the invention is represented in the accompanying drawings forming a part of this specification, in which similar characters of reference indicate corresponding parts in all the views.

30 Figure 1 is a side elevation of the border cutting machine; Fig. 2 is an end elevation of the delivery end of the border cutting machine; Fig. 3 is a plan view on the line 3—3 of Fig. 1 and showing more particularly the endless traveling band in register with the border; Fig. 4 is an enlarged edge view of part of the endless band; and Fig. 35 5 is a side elevation of one of the rollers around which passes the endless band.

40 The border cutting machine is mounted on a suitably constructed frame A on which are journaled the cutting roll B and the impression roll C between which passes the border D to be cut along one edge according 45 to the contour of the imprint on the paper, it being understood that the cutting roll B is provided with a continuous cutting edge conforming in shape to the contour of the said imprint. The border D passes over 50 and under a series of guide rollers E, E', E'' and E''' journaled on the main frame A, and of which the latter guide roller E''' is so located relative to the cutting roll B and the impression roll C that the border D passes 55 in an upwardly inclined direction from the

said guide roller E''' to and between the rolls B and C, as plainly indicated in Fig. 1. The cut border after passing between the rolls B and C passes between rolls C and F at the delivery side of the machine and finally passes between guide rolls G and G' to a suitable place of discharge. 60

On one side of the machine A is arranged an endless band or apron H having its lower run adjacent one edge of the border D as the latter passes from the guide roller E''' to and between the rolls B and C. This apron H is provided with pointers H' extending transversely and reaching onto the edge of the border D, and the said pointers H' are spaced apart equal distances corresponding to the distance between the repeating design or pattern D' on the border D. In practice, a design or pattern marked D'' is arranged on the border D adjacent one edge thereof to indicate the terminal points of the repeating design or pattern and as long as the pointers H' are in register with such marks D'' the border D is in register with the cutting edge of the cutting roll B. 70

The traveling band H passes around wheels I and I' provided at their peripheral faces with notches I'' adapted to be engaged by lugs or teeth H'' arranged on the inner face of the endless band H so that the latter is not liable to slip. The wheels I and I' are secured on shafts I''' and I'' journaled in bearings J and J', of which the bearing J is adjustably mounted on the frame A in the direction of the length of the band H 85 while the bearing J' is adjustably mounted in an up and down direction on a bracket J'' attached to the main frame A. The shaft I''' is driven in unison with the cutting roll B and for this purpose the shaft I''' is 90 connected by a train of gear wheels K, K', K'', K''' and K'''' with the shaft B' of the cutting roll B, it being understood that the gear wheel K is secured on the shaft I''' and the gear wheel K'''' is secured to the shaft B'. 95

The gear wheel K''' is mounted to rotate loosely on the shaft C' of the impression roll C and this gear wheel K''' is driven either at an equal speed or at an accelerated speed or a retarded speed relative to the impression roll C. For this purpose use is made of a mechanism under the control of the operator and preferably such, for instance, as is shown and described in the Letters Patent of the United States for a registering de- 100 105 110

vice for printing machines, No. 805,172, granted to me on November 21, 1905. This differential driving mechanism in its general construction is arranged as follows:

5 On the main frame A is mounted the driving shaft L driven by belt and pulley or other means from a countershaft, and on the said shaft are secured pulleys L', L² connected by belts L³, L⁴ with pulleys L⁵, L⁶, 10 mounted to rotate loosely on a shaft N journaled on the main frame A. The belt L⁴ is crossed so that the pulley L⁶ rotates in a reverse direction to that of the pulley L⁵. Between the pulleys L⁵, L⁶ is arranged a 15 double clutch N' mounted to rotate with and to slide on the shaft N adapted to be shifted by a shifting lever N² under the control of the attendant in charge of the machine. When the lever N² is moved in one direction 20 the clutch N' connects the pulley L⁵ with the shaft N, and when moved in the opposite direction the pulley L⁶ is connected with the shaft N.

On the shaft N is secured a sprocket 25 wheel O connected by a sprocket chain O' with a sprocket wheel O² mounted to rotate loosely on a shaft O³ journaled in a suitable frame A' forming part of the main frame A. The shaft O³ is provided with a gear wheel 30 P in mesh with a gear wheel P' secured on the shaft P² journaled in the frame A', and on the shaft P² is secured a sprocket wheel P³ connected by a sprocket chain P⁴ with a sprocket wheel P⁵ secured on the shaft C' of 35 the impression roll C. The sprocket wheel O² is connected by a differential gearing, such as shown in the patent above referred to, with the shaft O³ on which is fastened a sprocket wheel Q connected by a sprocket 40 chain Q' with a sprocket wheel Q² mounted on the hub R' of a bevel gear wheel R which in turn is connected by a return gearing with the gear wheel K³ previously mentioned and used for driving the gear wheel K⁴ of the 45 cutting roll B. The differential gearing and the return gearing above mentioned are the same as described in the Letters Patent above referred to so that further description of the same is not deemed necessary, it 50 being understood that by the arrangement described the cutting roll B is shifted forward or backward the desired distance until accurate registration of the cutting edge of the cutting roll B is had relative to the design or pattern on the border D, and as the 55 band or apron H is driven from the said cutting roll B and in unison with the same, it is evident that the pointers H' can be readily kept in register with the marks D² on the 60 border D.

It is further understood that should the 65 pointers H' move out of register with the marks D² then the attendant in charge shifts the lever N² correspondingly to increase or decrease the speed of the cutting roll B and

that of the apron H until the pointers H' are again in register with the marks D², and when this takes place the cutting edge of the roll B is also in register with the pattern on the border D.

Having thus described my invention, I claim as new and desire to secure by Letters Patent:

1. A border cutting machine provided with a cutting roll having a continuous cutting edge conforming in shape to the contour of the imprint on the border, and an endless traveling band driven from the said cutting roll and in unison therewith, the said endless band having one run arranged adjacent an edge of the border on the latter's passage to the said cutting roll, the said endless band having spaced registering means adapted to register with the spacing marks of the repeating design on the border. 75

2. A border cutting machine provided with a rotating cutting roll having a continuous cutting edge conforming in shape to the contour of the imprint on the border, an endless band having pointers spaced equal distances apart and adapted to indicate on the spacing marks of the repeating design of the border, and driving means for imparting a traveling motion to the said band from the said cutting roll. 90

3. A border cutting machine provided with a driven impression roll, a driven cutting roll, an endless traveling band having pointers spaced apart according to the repeating design of the border, driving means for driving the said band in unison with the cutting roll, and adjustable driving means for driving the said cutting roll in unison or at an accelerated or retarded speed relative to the said impression roll. 95

4. A border cutting machine, comprising a pair of revoluble rolls between which passes the border, one of the rolls being an impression roll and the other being a cutting roll having a continuous cutting edge conforming in shape to the contour of the imprint on the border, a guide roll over which passes the border to the said rolls, an endless band having pointers spaced equal distances apart, one arm of the said band being arranged adjacent an edge of the portion of the border extending from the guide roll to the said pair of rolls, the pointers on the said run being adapted to register with the spacing marks of the repeating design of the border, driving means for imparting a traveling motion to the said band from the said cutting roll, driving means for the said impression roll, and adjustable driving means for the said cutting roll to rotate the latter at the same or a retarded or accelerated speed relative to the said impression roll. 110

5. A border cutting machine, comprising a pair of revoluble rolls between which

passes the border, one of the rolls being an impression roll and the other being a cutting roll having a continuous cutting edge conforming in shape to the contour of the imprint on the border, a guide roll over which passes the border to the said rolls, an endless band having pointers spaced equal distances apart, one run of the said band being arranged adjacent an edge of the portion 10 of the border extending from the guide roll to the said pair of rolls, the pointers on the said run being adapted to register with the spacing marks of the repeating design of the border, the said endless band being 15 provided with lugs, guide wheels around which passes the said endless band and provided with notches for engagement by the said band lugs, a gearing for driving one of the said guide wheels from the said cutting roll for imparting a traveling motion to the said band in unison with the said cutting roll, driving means for the said impression roll, and adjustable driving means for driving the said cutting roll at the same 20 speed or at an accelerated or a retarded speed relative to the said impression roll.

6. In a border cutting machine, the combination with a pair of revoluble rolls between which passes the border, one of the 30 rolls having a continuous cutting edge conforming in shape to the contour of the imprint on the border, of supports, wheels mounted in the supports, an endless band mounted on the wheels and having pointers adapted to project over the edge of the border, the said pointers being spaced apart a distance equal to the distance between the 35 repeating design or pattern of the border,

and means for operating one of the said wheels from the cutting roll. 40

7. In a border cutting machine, the combination with a pair of revoluble rolls between which the border passes, one of the rolls having a continuous cutting edge conforming in shape to the contour of the imprint on the border, of adjustable bearings, 45 said bearings being adjustable at right angles to one another, wheels mounted in the bearings, an endless band mounted on the wheels and having pointers spaced apart 50 a distance equal to the distance between the repeating designs or pattern of the border, and means for operating one of the said wheels from the cutting roll.

8. In a border cutting machine, the combination with a pair of rolls between which the border passes, one of the rolls having a continuous cutting edge conforming in shape to the contour of the imprint on the border, of adjustable bearings, one of the 60 bearings being adjustable longitudinally and the other up and down, wheels mounted in the bearings, an endless band mounted on the wheels and having spaced pointers adapted to indicate on the border, and gearing between the wheel mounted in the bearing which is adjustable up and down and the cutting roll. 65

In testimony whereof I have signed my name to this specification in the presence of 70 two subscribing witnesses.

WILLIAM HUBELI WALDRON.
